UNITED STATES PATENT OFFICE.

CHARLES F. HEATH, OF WEST BRIGHTON, NEW YORK.

DUST-PAN.

SPECIFICATION forming part of Letters Patent No. 224,334, dated February 10, 1880.

Application filed January 9, 1880.

To all whom it may concern:

Be it known that I, CHARLES F. HEATH, of West Brighton, in the county of Richmond and State of New York, have invented an Improvement in Dust-Pans, of which the following is a specification.

Dust-pans have been made of sheet metal with a handle at the rear in the form of a loop, into which the toe of the foot is to be placed to hold the pan while the dust is swept into the pan. In this instance the loop is rigid, or nearly so, and it only allows the front part of the foot to be placed sidewise into such loop.

I combine with the dust-pan a handle and a spring foot-piece, that serves for supporting the back end of the dust-pan, and for holding the pan in line, or nearly so, with the foot, and for applying the downward pressure upon the foot-piece to hold the edge of the dust-pan to the floor, and at the same time to give to it a slight lateral sliding motion, to cause it to clear away any particles of grit that may intervene between the edge of the dust-pan and the floor, thus rendering the pan more efficient than heretofore.

In the drawings, Figure 1 is a section of the dust-pan and side view of the handle and foot-piece, and Fig. 2 is an inverted plan of the dust-pan.

The pan may be of any desired size or shape. That which is shown has a bottom, *a*, and rim *b* at the back and sides.

The handle *c* and foot-piece *d* are in one, and either of sheet metal or wire, bent to correspond generally to the outline of the sheet metal, as shown.

The handle and foot-piece are secured to the back of the dust-pan either by rivets passing through the metal of the handle and through the rim, or, in case where wire is used, a sheet-metal clip receives the wire and is soldered to the rim and extends beneath the back part of

the dust-pan, so as not to be easily pulled off when in use.

The handle portion *c* is of a suitable shape 45 for grasping with the hand. The foot-piece extends backwardly from the pan, and it slopes downward sufficiently to support the pan at an inclination, and for the outer or back end of the foot-piece to rest upon the floor when 50 the foot is not upon the foot-piece, as shown in Fig. 1. When the foot is passed from the rear in between the handle and spring foot-piece and pressed down upon said foot-piece, the latter is brought down flat upon the floor, 55 and the portion of the foot-piece next the dust-pan springs, and a certain definite and limited force is applied to hold the dust-pan down in the position shown by dotted lines. This prevents injury to the pan or foot-piece 60 by undue pressure upon the foot-piece, and at the same time the edge of the dust-pan is slid forward laterally a small amount, so that any slight obstruction, such as particles of grit, are worked out, and the edge of the dust-pan is brought into intimate contact with the 65 floor or carpet, so that dust can be easily swept into the pan by the person that is holding the dust-pan with the foot.

I claim as my invention—

The combination, with the dust-pan, of a handle and foot-piece in one, both extending to the rear of the pan, the foot-piece having a downward inclination and resting at the rear end upon the floor, and being made of spring 75 metal, so as to yield and come down flat on the floor by the pressure of the foot, substantially as and for the purposes set forth.

Signed by me this 7th day of January, A. D. 1880.

CHARLES F. HEATH.
